CLAIM

The ornamental design for an orthopaedic extremity support, as shown and described.

DESCRIPTION

FIG. 1 is a perspective view of an orthopaedic extremity support showing the preferred embodiment of my new design;

FIG. 2 is a front elevational view thereof;

FIG. 3 is a rear elevational view thereof;

FIG. 4 is a side elevational view, the opposite side view being a mirror image thereof;

FIG. 5 is a top plan view thereof;

FIG. 6 is a bottom plan view thereof; and,

FIG. 7 is a side elevational view thereof, the broken line showing is for illustrative purposes only and forms no part of the claimed design.

The straps in FIGS. 2–6 have been fragmentarily shown for ease for illustration.
